APPARATUS FOR DETERMINING THE MOTION OF WELL DRILLING TOOLS

Younger Neal and Glen G. Hebard, Chicago, Ill.,
assignors to The Pure Oil Company, Chicago,
Ill., a corporation of Ohio

Application December 13, 1937, Serial No. 179,476

6 Claims. (Cl. 73—30)

This invention relates to apparatus for indicating the motion of apparatus used in production of fluids from earth bores, and is particularly concerned with apparatus for indicating the movement of the drilling bit in percussion well drilling operations.

In the application of Richard H. Carr et al., Ser. No. 90,784, now Patent No. 2,163,665, entitled "Well drilling indicator" and the application of Richard H. Carr et al., Serial No. 177,962 filed December 3, 1937, entitled "Apparatus for use in connection with earth boring," there is disclosed apparatus for indicating the stresses in the line tools which occur during well boring and other well producing operations. From the line stresses obtained by means of the apparatus disclosed in those applications, it is possible to calculate the line stretch at any point during the stroke of the tools. However, in accordance with the apparatus disclosed in those applications, it is not possible to get an accurate picture of the motion of the drilling bit or other apparatus unless a diagram is plotted from calculations based on the stresses indicated by the apparatus. The length of the line or cable at the particular instant that it is subjected to a particular stress may be calculated according to the formula

$$S_1 = \frac{S}{A} \times \frac{L}{E}$$

where

S_1 = Stretch of the line or cable in feet due to the particular stress.

S = Stress in pounds.

A = Cross-sectional area of the line or cable in square inches.

L = Normal length of cable or line in feet when not subject to stress.

E = Modulus of elasticity of the line or cable.

A diagram can be plotted showing S_1 at each point in the up and down stroke of the line and beam to which it is attached. If to S_1 for each point determined, is added or subtracted the distance moved by the end of the walking beam, to which the line is fastened, a picture of the position of the drilling bit or other apparatus in the bottom of the hole can be obtained.

We have discovered that it is possible to indicate directly the motion of the drilling bit without resorting to calculations. Since the stretch in the line is directly proportional to the stress on the line within the elastic limit of the line, the drilling bit will move downwardly with increased stress on the line and upwardly with de-

creased stress on the line, assuming the beam is stationary. Thus, by recording or indicating increased stress by vertical downward motion and decreased stress by vertical upward motion, a true indication of the motion of the drilling bit is obtained. If the motion of the drilling bit, as thus determined, is superimposed on the motion of the beam end to which the drilling string is attached, a true picture of the actual motion of the drilling bit will be obtained.

In accordance with our invention we have provided apparatus by means of which the varying stresses in the drilling line are transmitted by a suitable dynamometer to a pressure responsive mechanism connected to an indicator which moves in a vertical direction. This indicator and pressure responsive mechanism is so arranged that when the line tension increases, and consequently the pressure on the pressure responsive means increases, the indicator moves vertically downward, and when the tension and pressure decreases, the indicator moves vertically upward. The indicator is mounted on a movable member which is adapted to be reciprocated by suitable means in harmony with the stroke of the beam to which the drilling tools are connected. The movable member is adjustable so as to reciprocate along a straight line corresponding to a curve plotted with distance moved by the beam from one end of its stroke to the other end as ordinates, and degrees of a semi-circle projected onto a straight line as abscissae, assuming each stroke of the beam corresponds to one hundred eighty degrees. Thus the indicator is simultaneously subjected to the motion caused by reciprocation of the beam and the motion caused by the varying tension in the drilling string of tools. As a result the indicator will move in substantially the same manner as the drilling bit moves at the bottom of the well and the operator is able thereby to determine how effective the operation is and can make suitable adjustment from time to time to obtain optimum conditions of operation.

One of the objects of our invention is to provide means for determining the motion of well drilling or other well operating tools.

Another object of the invention is to provide apparatus whereby the motion of a drilling bit or other well operating tool, which is not visible, can be reproduced.

Another object of the invention is to provide means for enabling the control of well drilling or other well operations and for rendering such operations more efficient.

Further objects of the invention will become apparent from the following description and accompanying drawings, of which,

Fig. 1 is a front elevational view of apparatus in accordance with our invention, with a portion thereof cut away.

Fig. 2 is a front elevational view of the apparatus shown in Fig. 1 but in a different position.

Fig. 3 is a plan view of the apparatus shown in Fig. 1 with parts thereof removed.

Fig. 4 is a front elevational view of a portion of the apparatus shown in Figures 1 and 2.

Fig. 5 is a vertical cross-sectional view taken on the line 5—5 of Fig. 1.

Fig. 6 is a vertical cross-sectional view of the gear box forming part of the apparatus shown in Figures 1 and 2.

Fig. 7 is a horizontal cross-sectional view taken on the line 7—7 of Fig. 6.

Fig. 8 is a vertical cross-sectional view taken on the line 8—8 of Fig. 7.

Fig. 9 is a graph showing the paths described by the beam and the drilling bit during percusion well drilling operations.

Referring more particularly to Figures 1 to 3, numeral 1 indicates generally a frame, the parts of which are preferably cast from steel or aluminum alloy and assembled so that it is rectangular in shape. The frame may consist of ends 3 and 5 which are held in spaced relation by means of tie bars 7. The left end 5 of the frame is provided with vertical flanges 9 to which the plates 11, having arcuate edges 13, are adapted to be bolted by means of bolts 14. The plates 11 are provided, adjacent the edges 13, with suitable holes 15. The arcuate edge 13 has a radius R (Fig. 1). The frame may be covered by suitable plates of steel or aluminum and the front plate is preferably provided with a frosted glass window (not shown) in front of the indicator, to be subsequently described.

Mounted in the frame adjacent the front thereof are the parallel rails 17 and 19. The rails are held in spaced vertical relation by means of the tie bars 21 and 23. The left hand ends of the rails are fastened to the plates 11 at the points 25 and 27 by means of nuts and bolts 28 passing through the holes 15. The rails are pivotally supported adjacent the right hand ends thereof by means of the shaft 29 passing through the tie bar 21 intermediate the ends thereof. Copper conductor bars 31 and 33 are fastened to the lower rail 19 and suitably insulated therefrom and from each other. The bars are connected by wiring to the batteries 35 or other suitable source of electric current. The rails 17 and 19 have longitudinal grooves 37 facing each other for the purpose of permitting the rollers 39 of the carriage frame 41 to ride therein.

The carriage frame 41 is preferably cast out of aluminum alloy for purposes of lightness. As shown in Fig. 4, the frame is cast with the openings 43 in order to add to its lightness. The radial arms 45 extend from points adjacent the outer edges of the carriage frame to the center thereof, where they join together to form hub 47. Although as shown in Fig. 4, the carriage frame is substantially square, it may be rectangular or other shape. The rollers 39 are ball bearing and mounted on pins 49, hammer- or shrink-fitted into the carriage frame 41 adjacent the corners thereof. These rollers are adapted to freely roll in the grooves 37 of the rails 17 and 19 and maintain the carriage in place on the rails.

A steel pin or shaft 51 (Fig. 5) is hammer-

shrink-fitted into the hub 41 of the carriage frame 41. A rotatable disc 53, preferably of smaller diameter than the distance between the rails, is mounted at its center on pin 51 by ball bearings. The disc 53 is provided adjacent its lower edge 5 with gear teeth 55. A worm 57 mounted on the carriage frame by means of bracket 59 is adapted to engage the gear teeth 55. The pinion may be rotated by means of a handle 61.

A cylinder housing 63, having flanges 64, is rigidly mounted on the upper part of the disc 53 by means of bolts 65 passing through holes in the flanges. The upper end of the housing 63 is provided with a hollow, internally threaded coupling 67 to which a flexible hose is adapted to be connected. A cylinder 68 fits snugly within the housing 63. A sliding plunger 69 is snugly mounted in the cylinder 68 and is provided with an integral collar 71 intermediate the ends of the plunger. The lower end of the housing 63 is provided with an opening 73 through which the lower end of the plunger 69 passes. The diameter of this opening is smaller than the diameter of the collar 71. The collar is mounted between the lower ends of the housing 63 and the cylinder 68 and limits the movement of the plunger in either direction.

Referring more particularly to Figures 1, 2 and 3, bracket 75 is rigidly mounted on the upper right hand side of the disc 53. Bracket 75 is formed with bifurcated arm 77. The inner faces of the bifurcation are machined to receive the upper end of the arm 79 and an intermediate portion of the arm 81. A pin 83 is rigidly mounted in the bifurcated arm 77 and the arms 79 and 81 are pivotally mounted on the pin by means of ball bearings. The arm 81 is also pivotally connected at the point 85 to the upper end of a rod 87. The rod 87 is vertically mounted directly below the plunger 69 and the lower end thereof is slidably mounted in the cylinder 88 which in turn is threaded into swivel bearing 89. The bearing 89 is held in place on the disc 53 by means of the bracket 91. The lower protruding portion 92 of the cylinder 88 is hexagon or other suitable shape to permit it to be engaged by a wrench and be turned thereby adjusting the tension of coil spring 93. The calibrated coil spring 93 is mounted on the rod 87 between lip 95 and the upper face of the cylinder 88. The lower end of the plunger 69 is adapted to contact the roller 96 mounted on the pin 85.

A link 97 pivotally connects the left hand end of the arm 81, by means of pin 98, to another link 99. The link 97 is pivotally connected to the link 99 intermediate the ends thereof by the pin 101. The link 99 is pivotally connected by means of pin 102 at the end 103 to the bar 105 which is vertically and rigidly mounted on the disc 53 at the points 107 and 109. The bar 105 is spaced from the face of the disc 53 by means of pins 111. The indicator arm 113 is pivotally fixed to the other end of the link 99 by means of the pin 115 and is also pivotally fixed to the end 117 of the arm 79 by means of the pin 119. The indicator arm 113, as shown in Fig. 3, is cast integrally with the spaced arm 121. The various links and arms heretofore described are arranged between the inner arm 121 and main arm of the indicator arm 113, and the various pins connecting the indicator arm to the several links and arms pass through both arms of the indicator.

All pivots are ball bearing mounted. It will be seen that the only fixed pivots are the pins 83 and 102. The linkage shown and described is so ar-

ranged as to cause the end 123 of the indicator 113 to move along a vertical line when motion is imparted to the rod 87. Light socket 125 is mounted on the end 123 of indicator 113 and is 5 adapted to receive a small electric light bulb. The socket 125 is adapted to be connected by suitable wires (not shown) to contact points or brushes 127 and 129 (Figs. 1 and 2) and in turn are connected to the brushes 131 and 133 which 10 contact the copper bars 31 and 33. The brushes and contact points are located in the bracket 135, fastened to the lower end of the carriage frame 41.

Referring again to Figures 1 to 3, the left hand 15 end of a connecting rod 137 is pivotally mounted on a pin 139, which is hammer- or shrink-fitted into the left hand end of the carriage frame 41 intermediate the upper and lower ends thereof and extends horizontally from the back face 20 thereof. The right hand end of the crank arm is pivotally fixed to one end of a crank 141 by means of pin 143. The other end 145 of the crank is suitably weighted for counter-balancing purposes.

Referring more particularly to Figs. 3, 6, 7 and 8, a gear box 146 is suitably mounted by means of bolts 147 on brackets 149 formed integrally with the frame end 3. A shaft 151 extends horizontally into the gear box through the housing 153 in which is mounted the bearing 155. The shaft is also supported by bearing 156. To the outer end of the shaft 151 is keyed a sprocket 157 by means of key 159. On the inner end of the shaft 151 is fastened a gear 161 which is adapted to rotate with the shaft. A horizontal shaft 163 in the same horizontal plane as the shaft 151 by running perpendicular thereto is mounted in the gear box in the bearings 165 and 167. One end 25 of the shaft 163 extends outside of the gear box and the crank 141 is keyed thereto or otherwise rigidly mounted thereon. A gear 171 is rigidly mounted on the shaft 163 inside the gear box adjacent the inside wall of the box and is adapted to engage the gear 161. A second gear 40 45 50 55 60 65 70 75 173, smaller than the gear 171, is mounted on the shaft 163 adjacent the opposite wall of the gear box. This gear does not engage the gear 161. A vertical shaft 175 mounted in bearings 177 and 179 and held in place by retaining nut 180 extends into the gear box and has a gear 181 rigidly mounted on the inner end thereof. The gear 181 is adapted to engage the gear 173. The upper end 183 of the shaft 175 extends through an opening in the upper part of the gear box. The opening is closed by a cap 185 secured to the box by means of bolts 187. A suitable pipe 189 having a cap 191 is screwed into the lower portion of the gear box in order to permit introduction of lubricant.

The tie bar 21 is pivotally mounted on the outer end 29 of the shaft 163.

The apparatus just described is used in the following manner: A sprocket is placed on the driving shaft of a well drilling rig (not shown) and the sprocket 157 is connected thereto by means of a chain (not shown). The coupling 67 at the top of the cylinder 63 is connected by means of a flexible hose or line to a dynamometer head fastened to the end of the walking beam of a well drilling rig. The drilling string or other string of tools is suspended from the dynamometer in a manner similar to that shown and disclosed in the aforementioned application, Carr et al. Ser. No. 90,784, or the patent to Lake 1,739,724. The rotation of the drive shaft causes rotation of the

shaft 151 and in turn of the crank 141. As the crank rotates it causes the carriage to reciprocate on the rails 17 and 19. At the same time the variation in tension on the string of drilling or other tools will be imparted to the plunger 69 and the 5 rod 87 against the tension of the spring 93. Through the linkage heretofore described, the end 123 of the indicator 113 will be caused to move along a vertical line. Due to the simultaneous motion imparted to the carriage carrying 10 the indicator arm and the motion imparted to the end of the arm by the variation in tension in the string of tools at each portion of the stroke of the string, the end of the indicator arm will define or trace the outline of an indicator card 15 showing the tension at each point in the stroke of the drilling string.

As will be seen, increase in tension in the line will cause a downward movement of the end of the indicator arm and decrease in tension will 20 cause upward movement. Since the change in length of the line is directly proportional to the tension in the line, the motion of the arm can be calibrated so as to indicate the exact change in length of line from point to point in the stroke. 25 The path of the light bulb in the end of the indicator 113 may be observed through a frosted glass window (not shown) placed in the frame cover plate. The size of the glass should be sufficient to provide vision of the light bulb at all times. In 30 apparatus of this nature, a window approximately ten inches square will provide sufficient area. Thus the operator is enabled to continuously watch the path of the light bulb and determine 35 whether the tools are moving in the same direction as the end of the walking beam to which they are fastened, or are moving out of harmony therewith.

As shown in the graph in Fig. 9, the beam end 40 movement through each one hundred eighty degrees during the up and down strokes is represented by the line O—O'. During the up stroke of the beam, when the crank moves through an arc of one hundred eighty degrees, the beam moves upward from O to O'. During the next 45 one hundred eighty degrees of revolution of the crank, the beam moves downward from O' to O. If the tracks 17 and 19 are left in the horizontal position, shown in Fig. 1, the light bulb will trace a path indicated by the line A' B' C' D' E' F' G' 50 55 60 65 70 75 80 85 90 95 A'. This diagram indicates that on the down stroke of the beam the drilling bit descended more slowly than the beam along the A' G' and that when the beam began its upward stroke the tension of the line suddenly increased and as a result the line stretch caused the tools to drop the distance A' B'. At the point B', the tools suddenly rebounded to the point C' and then stretched again to the point D', rebounded upwardly to the point E', then stretched slightly to the point F', when the beam was almost at the top of the stroke and then when the beam reached the top of the stroke the line again contracted until the drilling bit was at the position G'. Although this diagram represents the 65 stretch and contraction in the drilling line from time to time, it does not represent the exact position of the drilling bit at any point in the beam stroke. In order to obtain these observations it is necessary to rotate the tracks about the pivot 70 75 80 85 90 95 98 100 105 110 115 120 125 130 135 140 145 150 155 160 165 170 175 180 185 190 195 198 200 beam, is either added to or subtracted from the distance the tools move due to stretching or contracting of the line. After the track has been rotated to the required position and fastened in place on the plates 11, the disc 53 is rotated by means of the worm 57 and handle 61 to a position such that the direction of movement of the end 123 of the indicator 113 is in a vertical direction when the carriage is motionless. When the apparatus is so adjusted, the path traced by the light bulb is represented by A'' B'' C'' D'' E'' F'' G'' A''. This curve represents the position of the drilling bit at each point in the stroke and, thus, the position of the drilling bit at each point in the beam stroke can be accurately observed and the operator can determine whether or not the bit is striking bottom and when it strikes bottom. By proper adjustment of the speed and motion of the walking beam, the operation can be improved so that the bit strikes bottom at the bottom of the beam stroke and full impact of the stroke is obtained. By calibrating the spring 93 and the extent of motion of the carriage 41, it is merely necessary to measure the height of any point of the curve from the bottom point and multiply by the scale factor in order to determine the actual distance the drilling bit moves from one point to the other.

The length of the line O—O' corresponds to the distance which the carriage moves in either direction and its horizontal projection X—Y is divided into 180° as shown. The distance O'—Y corresponds to the beam stroke and is drawn to the scale which corresponds to the calibration of the coil spring 93. For example, if coil spring 93 is calibrated so that for a line stress producing a stretch of one foot in the line the spring 93 will permit a vertical movement of one inch by the indicator bulb 125, then each inch of the distance O'—Y will represent one foot distance of travel of the beam, so that when the movement caused by the line stress is superimposed on the movement of the beam, the two will add together in the same units and by merely multiplying the resulting distance by twelve, the number of inches of movement of the tool at the bottom of the well can be determined.

It is apparent that any scale can be used, but in the example just given in order to determine the distance in inches from the diagram, the scale factor would be twelve. From the distance the end of the beam travels during a stroke and the distance the carriage travels on each stroke, the angle between the line O—O' and O—Y can be determined and the carriage then rotated to this angle.

When the carriage is rotated to the required angle, it will represent the height of the beam at each point in the stroke on the reduced scale. Therefore, when the stretch of the line is added to the height of the beam at any point, the position of the tool at the bottom of the well is precisely shown by the indicator. As previously pointed out, the diagram showing the position of the tool is represented by the letters A'' B'' C'' D'' E'' F'' G'' A''. It will be seen from this diagram that in this particular case the lowest point of the drilling bit, namely, B'' does not occur at the lowermost point of the beam stroke which is represented by the point O, but occurs some time during the upward stroke of the beam. In a normal drilling operation the line is shorter than that which would be required in order for the drilling bit to rest on the bottom of the hole when the beam is at its lowermost position. It is

only when the beam starts on its upward stroke and increased tension of the line causes stretching that the bit goes downwardly and strikes bottom. Thus, at point A'' which is the point of lowermost position of the beam, the bit is not 5 on bottom. When the beam has travelled upwardly a distance corresponding to approximately 40°, the bit hits bottom. The line then rebounds as shown at C' and again stretches to D'', whereupon it rebounds again to E'' and 10 stretches slightly to F''. The drilling bit is at its highestmost position G'' at the end of the upward stroke of the beam. The jagged line B'' C'' D'' E'' F'' is caused by the bouncing of the line during the upstroke of the beam. 15

The measurements of height are taken from the lowestmost point B'' where the tool strikes bottom. It will be seen that the vertical distance from the point B'' to the point G'' is greater than the distance from the point O' to Y and the difference in distance is the distance which the line stretches in order for the tool to hit bottom. The bottommost point on the diagram O'XY was drawn adjacent to the diagram A'' B'' C'' D'' E'' F'' G'' A'' merely to show how closely 25 the downstroke of the diagram G'' A'' corresponded to the plotted stroke of the beam.

In order to obtain a permanent record of the motion of the drilling tools, the cap 185 may be removed from the gear box and a suitable recording device (not shown) may be fastened to the upper end of the shaft 175. This indicator may be connected to the dynamometer by suitable hose or line and a permanent chart record thus obtained of the stretch of the drilling or 35 other line at each point in the stroke thereof.

Instead of using the chain drive from the driving shaft to operate the device, the shaft 151 may be connected directly to the walking beam and instead of turning the crank 139 through a complete revolution, the crank may oscillate back 40 and forth. If desired, the gear box may be dispensed with entirely and suitable connections from the walking beam or drive shaft of the drilling rig 3 of the crank arm 141 made in order to 45 oscillate the arm.

Instead of providing holes in the plates 11 along the edge in order to adjust the position of the tracks, the plates may be furnished with an arcuate track adapted to engage gear wheels 50 fastened to the tracks and the tracks can be moved into position in the same manner as the disc 53 is rotated.

The entire casing containing the device shown and described may be approximately three to 55 four feet long by one and one half to two feet wide and the same height. By using light materials in the construction thereof the entire apparatus may be made to weigh from one hundred to one hundred fifty pounds so that it 60 can easily be conveyed from place to place.

It will be seen that we have provided novel apparatus for indicating and observing the motion of a drilling bit, or other well operating tools, which is subjected to reciprocating motion, there- 65 by eliminating the uncertain and undependable methods heretofore used in controlling and regulating such operation.

What we claim is:

1. Apparatus for reproducing motion of a tool 70 connected to the lower end of a substantially vertical, reciprocating, elastic line which comprises means for translating increase in line stress into vertical downward motion or for translating decrease in line stress into vertical 75

- upward motion, means for translating the reciprocating motion of the line into motion corresponding to a curve plotted with the distances the upper end of the line moves during each stroke as ordinates and degrees of a semi-circle projected onto a straight line as abscissae, assuming that each stroke of the line corresponds to one hundred eighty degrees, and means for producing a visual diagram of the combined effects of the two motions.
2. Apparatus for reproducing motion of a tool connected to the lower end of a substantially vertical, reciprocating, elastic line which comprises a carriage mounted on tracks and adapted to reciprocate thereon, means for reciprocating said carriage, means for rotating said tracks and said carriage in order to enable the carriage to reciprocate along a line at an angle to the horizontal, an indicator mounted on said carriage, a fluid pressure responsive means connected to said indicator in such manner as to cause said indicator to move in a straight line, and means to enable said indicator to be adjusted to move in a straight vertical line, regardless of the position of said carriage.
3. Apparatus for reproducing motion of a tool connected to the lower end of a substantially vertical, reciprocating, elastic line which comprises a carriage slidably mounted on tracks, means for reciprocating said carriage, means for rotating said tracks from a horizontal to an angular position in the same vertical plane, about a fixed axis, a rotatable disc mounted on said carriage, means for rotating the disc, an indicator mounted on the disc, and pressure responsive means mounted on said disc and connected to said indicator in such manner as to impart straight line motion thereto.
4. Apparatus for reproducing motion of a tool connected to the lower end of a substantially vertical, reciprocating, elastic line which comprises means for translating increase in line stress into vertical downward motion or for translating decrease in line stress into vertical upward motion, means for simultaneously translating the reciprocating motion of the line into motion corresponding to a curve plotted with the distances the upper end of the line moves during each stroke as ordinates and degrees of a semi-circle projected onto a straight line as abscissae, assuming that each stroke of the line corresponds to one hundred eighty degrees,
- means for superimposing the translated line stress motion upon the translated reciprocating motion of the line and means for obtaining a visual diagram of the superimposed motions.
5. Means for automatically and visually reproducing the motion of a subterranean tool connected to the end of a substantially vertical, reciprocating, elastic line which comprises means for translating stress at each point in the stroke of the line into straight line motion at the surface of the earth, proportional to the stretch of the elastic line produced by the stress, means for translating the reciprocating motion of the elastic line into straight line motion corresponding to a curve obtained by plotting in the direction of the straight line motion into which the stress is translated, distance moved by the upper end of the elastic line, and by plotting at right angles with said direction, degrees of a semi-circle projected onto a straight line, means for superposing the straight line motion corresponding to the stretch of the elastic line on the motion corresponding to the reciprocating motion of the elastic line and means for producing a visual diagram of the combined effects of the two motions.
6. Apparatus for reproducing motion of tools located in earth bores and connected to a substantially vertical, reciprocating, elastic line which comprises a carriage slidably mounted on horizontal tracks, means for reciprocating said carriage, means for rotating said tracks about a fixed axis to an angular position in the same plane, a rotatable disc mounted on said carriage, means for rotating said disc, an indicator arm pivotally mounted on said disc, a series of interconnected links mounted on said disc and connected to said arm in such manner that movement of said links imparts substantially straight line motion to the end of said indicator arm in a plane parallel to the plane in which the carriage is adapted to reciprocate, a cylinder adapted to be connected to a source of fluid pressure, mounted on said disc, a piston slidably mounted in said cylinder, one end of said piston extending outside of said cylinder and adapted to operatively engage said links, and a coil spring mounted on said disc in a position to oppose the movement imparted to said links by said piston.

YOUNGER NEAL,
GLEN G. HEBARD.
